[57] CLAIM

The ornamental design for a wheel for in-line skates, as shown and described.

DESCRIPTION

FIG. 1 is a perspective view of the wheel for in-line skates embodying the present invention;

FIG. 2 is a front view;

FIG. 3 is a rear view;

FIG. 4 is a top view;

FIG. 5 is a bottom view;

FIG. 6 is a side view; and,

FIG. 7 is the other side view.

The wheel for in-line skates is symmetrical so that it has the same appearance from the top, the bottom, and both sides.
